CARTON

John W. Cox, Chicago, Ill., assignor to Self-Locking Carton Co., Chicago, Ill., a corporation of Illinois

Application December 22, 1941, Serial No. 423,885

2 Claims. (Cl. 229—28)

This invention relates to improvements in cartons for packing fragile articles such as eggs. More particularly it pertains to collapsible cellular cartons such as may be formed from a unitary blank of paper board or similar sheet of material and having correlated features for automatically locking and bracing it in set-up condition in which it will effectively retain, protect and cushion contained eggs.

A general object of the invention is the provision of a carton which is simple yet sturdy and durable in construction, economical in material and cost of manufacture, adapted to be fabricated in a flattened or collapsed condition in which it may be shipped conveniently, and susceptible of being quickly and easily set up in condition for reception of the intended articles and of being easily closed and secured, without the use of machines or other mechanical contrivances.

Specifically, it is an object of the invention to provide such a container having a central longitudinal partition and a plurality of transverse partitions, all formed in a unitary blank and so related as to provide interlocking members and buttresses adapted to engage, support and secure one another in erected positions wherein they cooperate with the side, top and bottom walls of the carton to form compartments or cells and to sustain the carton in stable set-up condition.

More specifically, an object of the present invention is the provision of a collapsible cellular carton formed of a unitary sheet and having a central longitudinal partition cut out to provide openings into which transverse partitions may be swung into retentive engagement with retaining fingers shaped to form hooks below the ridge of the longitudinal partition so that the latter affords series of backbone supports for the transverse partitions, the backbone supports and retaining fingers serving to maintain the longitudinal partition in upright position and in alignment as and after the positioning of the transverse partitions take place.

These and other objects of the invention will in part be apparent and will in part appear hereinafter from a consideration of the following described preferred embodiment.

For a fuller understanding of the nature and objects of the invention reference may be had to the following detailed description taken in connection with the accompanying drawings, in which

Fig. 1 is a plan view illustrating a preferred form of die-cut and scored rectangular blank to

be folded to form a knocked-down container embodying the present invention;

Fig. 2 is a perspective view depicting the completed container in knocked-down form, but partially unfolded, to show the folds and glue points;

Fig. 3 is a perspective view with the cover broken away, illustrating an initial step in erecting the container showing the body fully expanded and the end transverse partitions oppositely drawn into interlocking engagement with the longitudinal partition;

Fig. 4 is a similar perspective view illustrating the carton completely erected, with all partitions interlocked;

Fig. 5 is an end view of the set up carton shown in Fig. 4, illustrating particularly the bottom extension cushioning members; and

Fig. 6 is an end view similar to Fig. 5 illustrating the completed and filled carton with the cover in closed and locked position and serving to illustrate how the foot elements of the longitudinal and transverse partition members sustain the bottom, and the top spacers act as cushioning supports under the cover.

In Fig. 1 of the drawings there is illustrated a generally rectangular blank which has been die-cut and scored to form a glue flap 10, a cover 11, a cover locking flap 12, side walls 13, 13', bottom sections 14, 14', and a plurality of cross or transverse partitions 15. The bottom sections 14, 14' are set off by crease lines *a* from a central strip 16 which is creased radially and die-cut to provide a series of bilaterally symmetrical apertures and form retaining members 17 and latching members 18, all positioned so that the symmetrically opposed ones will be caused to coincide by folding the central strip 16 along its longitudinal median line. The strip may be secured by adhesive in such folded condition to form a longitudinal partition carrying groups of longitudinally extending retaining fingers or hooks 17 spaced intermediate the top and bottom margins of the longitudinal partition. These retaining fingers preferably have straight upper edges spaced below the upper edge of the longitudinal partition. The under edge of each retaining finger preferably is curved to permit ready positioning of each of the transverse partitions as hereinafter described.

An important feature of the construction is the provision of backbone supports formed of the strips 16' remaining between the cut-out portions in the longitudinal partition. These backbone supports provide abutting and bracing members adjacent the upright planes of the cross partitions for cooperation with the sides of the cross

partitions extending above the retaining fingers. These bracing members 16' are on the sides of the cross partitions from which the upper portions thereof are rotated in the setting up operation. The backbones also guide the transverse partitions to aid entry of the retaining fingers in the openings thereof. Along each side of the central section 16 additional foot lugs 20 are formed as lateral extensions of said sections, and cushion tabs 19 are partially cut from bottom sections 14 but remain hingedly attached thereto. Also in the bottom section 14, 14' are formed slotted apertures 21 which, together with the lugs 19 and 20, will have their functions more fully set forth hereinafter.

Referring to the series of cross partitions 15, it will be seen that certain of them have been provided centrally with a triangular opening 22 and that two of the inner cross partitions have angular notches 23. Those cross partitions having the triangular openings also have extending lugs or feet 24, and all except the two end cross partitions are also provided with a top extension 25.

Referring now to the carton as shown in knock-down or collapsed condition in Fig. 2, it will be seen in the slightly expanded position thereof that the blank of Fig. 1 has been folded along the score or crease lines there indicated by dotted lines, a, b, c, d, e and f, in a manner such that the glue flap 10 is laid flat against the inner surface of the side wall 13' throughout the length thereof from one side of the blank to the other, and that the longitudinal partition panel 16 has been folded along its central line a so that its symmetrical halves are in register. The glue flap is adhesively affixed to the wall 13 in that position, and the abutted halves of the longitudinal partition members 16 are glued to each other down to the fold lines b to form a two ply central longitudinal partition having a series of aligned intermediately disposed retaining elements or fingers 17 each directed toward the middle of the receptacle, leaving the bottom sections 14, 14' free to swing apart or expand to form the receptacle bottom.

In Fig. 3 it will now be seen that the receptacle has been fully expanded or unfolded widthwise and that the endmost cross partitions have been swung to vertical positions on hinge lines g along triangular webs 26 by which each cross partition is connected at one end to side wall section 13' and at its other end to glue strip 10 (see also Fig. 4). At this position of the transverse partitions, their extending appendages or feet 24 have been snapped into and extend through the slotted apertures 21 and retain said partitions upright, and the two-ply retaining members 17 of the longitudinal partition 16 extend through the triangular openings 22, and, bearing on the lower margins of said openings, hold the cross partitions down. By similar manipulation the remaining cross partitions are likewise brought into latched set-up position. For example, an operator, by inserting the index and middle fingers of each hand on opposite sides of the longitudinal partition in each pair of end compartments and by drawing the hands in opposite directions against the endmost transverse partitions, will rotate the latter to the positions shown in Fig. 3. The operation is repeated with the two next succeeding transverse partitions from each end of the carton and finally the middle transverse partition is similarly swung down and latched behind the upstanding projection 18. It will be appre-

ciated that after the carton is unfolded widthwise, these operations may be performed by a few quick movements of both hands working simultaneously, so that the carton may be quickly set up in condition for filling.

Fig. 4 shows the receptacle set up and ready for filling and illustrates how the retaining members 17 are engaged in the triangular openings 22 to retain the transverse partitions with their extending feet 24 passing through the apertures 21. The angular cut-out portions 23, however, are not engaged by retaining members 17, but after frictionally engaging and passing along the cam-like top surfaces of member 18, snap into the deeper notches at the ends thereof, where they seat and are firmly retained in position. By further reference to Figs. 5 and 6 it will be observed that the lugs or feet 20 of the longitudinal partition now are projected vertically downwardly from the medial line of the bottom to a point which is in line with or substantially flush with the ground line or bottom edges of the side walls 14-14', especially when the carton is filled, and there to support almost all of the area of the bottom sections away from the supporting surface so that they act as cushioning members. The cross partitions 15, with the exception of the endmost ones, extend above the longitudinal partition elements 16' by virtue of the extensions 25.

In Fig. 6 it will be seen that the cover 11 is held spaced from the contents of the container by virtue of the extension members 25 of the cross partition so that downward shock or thrust received by the cover is transmitted through those partitions and to the supporting surface through their feet 24 which extend through the bottom slots 21. Likewise, any downward pressures received by the central partition member 16 are transmitted to the supporting surface through its feet 20. Accordingly, the contents of the carton are effectively safeguarded from crushing pressures by the vertically disposed partition members. Eggs placed in the cells are held apart from one another by the partitions, including the retaining members 17 of the longitudinal partition, and they are cushioned from the supporting surface by the elevated bottom sections 14 and 14'. The apertures in those sections formed by displacement of the feet 20 and tabs 19 are adapted to receive and locate the points of eggs which rest on those tabs, said tabs contributing an auxiliary cushioning effect. The cover is secured in the closed position illustrated in Fig. 6 by engagement of the hooks of the locking strip 12 under some of the gusset ledges 26.

By virtue of the interlocking cooperation of the cross partitions with the longitudinal partition and bottom sections, the parts are securely retained in their set-up relationship, wherein the partition members stand in vertical planes so as to constitute effective load-carrying members which relieve the side walls and bottom sections of vertical thrust, the longitudinal partition elements 16' cooperating with the top extensions 25 to brace the latter against flexing under weight imposed on the cover. In its set-up condition and with the cover closed, the carton will be quite stable and stiff and will afford effective protection for its contents.

It will thus be seen that by means of the present invention the objects hereinbefore specified are attained, and since certain changes may be made in the above described construction and different embodiments of the invention could be made without departing from the scope thereof,

it is intended that all matter contained in the above description or shown in the accompanying drawings shall be interpreted as illustrative and not in a limiting sense.

It is also to be understood that the following claims are intended to cover the invention in its generic and specific aspects.

What I claim is:

1. A knock-down cellular carton, comprising oppositely arranged side walls, cross partitions attached at their ends to said walls in a series and hinged above their centers to swing downwardly from generally horizontal positions to spaced upright positions, a longitudinal partition joined to said side walls by bottom wall sections and having longitudinally directed retaining members traversing the upright planes of said cross partitions and also having upstanding bracing members extending above the planes of the hinges and tops of said retaining members adjacent the upright planes of said cross partitions, at least some of said cross partitions having medial apertures spaced from their upper and lower margins and located to receive said retaining members as the cross partitions are swung to upright positions, said cross partitions also having upwardly ex-

tending portions above said apertures in position to abut said bracing members when the cross partitions are in upright positions.

2. A collapsible cellular carton, comprising oppositely disposed side walls, cross partitions having their opposite ends hinged to upper portions of said walls to permit said cross partitions to swing from positions along the upper ends of the side walls to upright position between the side walls, a longitudinal partition joined to said walls by bottom sections and having longitudinally extending slots in which portions of said cross partitions may be engaged when swung to upright positions, said bottom sections having slots disposed to receive lower end portions of at least some of the cross partitions when same are standing in upright positions, the longitudinal partition and at least some of the cross partitions having portions interengageable to retain the cross partitions against withdrawal upwardly from the bottom sections, and upstanding bracing members on said longitudinal partition extending upwardly in abutting relation with portions of the cross partitions above their hinge line.

JOHN W. COX.
